March 24, 1931.

C. C. CAMERON

1,797,714

GARMENT

Filed May 17, 1929

2 Sheets-Sheet 1

FIG. I.

WITNESSES

Thomas W. Kerr Jr.
George M. Meekamp

INVENTOR:

Celina C. Cameron,
BY Tracy, Gandy

ATTORNEYS.

March 24, 1931.

C. C. CAMERON

1,797,714

GARMENT

Filed May 17, 1929

2 Sheets-Sheet 2

FIG. IV.

FIG. III.

FIG. II.

WITNESSES

Thomas W. Kerr Jr.
George M. MacDowell

INVENTOR:

Celina C. Cameron,
BY Folley Davis
ATTORNEYS.

UNITED STATES PATENT OFFICE

CELINA C. CAMERON, OF ERIE, PENNSYLVANIA

GARMENT

Application filed May 17, 1929. Serial No. 363,765.

This invention relates to garments of the negligee class and of a type intended more particularly for women.

The object of my invention is to provide a slip-on garment of the kind referred to which is simple in design, yet highly attractive in appearance; which is easily and quickly put on or taken off; and which ordinarily affords complete protection, but when desired permits the back of the wearer to be exposed for sun or heat treatment to the exclusion of all other parts of the body.

In the drawings Fig. I is a view showing my improved garment laid out flat.

15 Figs. II and III are illustrations showing how the garment is ordinarily worn; and,

Fig. IV is an illustration, similar to Figs. II and III, showing how the garment is used incident to sun bath treatments with the back 20 of the wearer exposed.

With more specific reference first to Fig. I of these illustrations, it will be observed that my novel garment is made from a substantially oblong piece of fabric with a centrally disposed opening 10 nearer the upper short edge marked 11, and with aligned lateral incisions 12, 13 into its longer sides at a region intermediate said opening and the bottom edge 14. By such construction I set apart 25 an upper rectangular cape-like portion 15, and a bottom or skirt portion 16, the two subdivisions being accordingly joined by a narrower waist portion 17 between the inner ends of the incisions 12, 13. As shown, the skirt 30 portion 16 of the garment is laterally offset somewhat in one direction relative to the upper portion 15, or patterned slightly trapeziform in outline, for a purpose hereinafter explained. The garment may be ornamented 35 by attaching a border of lace or braid around the edges of the upper or cape portion 15 as at 18, and along two edges of the skirt portion 16 as at 19, 20. The opening 10 for the head may likewise be embellished with a collar edging 21 of lace or braid; and the garment furthermore provided with tie strings 22, 23 which form end continuations of the upper edge of the skirt portion 16.

With the upper edge of the cape portion 15 thrown rearward, the garment is slipped over the head so that said cape portion divides over the shoulders. The skirt portion 16 is thereupon wrapped about the lower part of the person, and the garment finally secured by bringing the tie strings 22, 23 around the 55 waist and tying them into the form of a bow, all as shown in Figs. II and III. Relative proportioning and offsetting of the skirt portion 16 in the manner previously pointed out, it will be seen, predetermines overlapping of 60 substantial margins of the meeting edges and disposal of the parting line at one side of the person. In this connection it is pointed out that the lace edge 19 of the skirt portion 16 is placed uppermost and appears as an ornamentation which materially enhances the attractiveness of the garment. Now since the end 11 of the cape portion 15 hangs free, it is capable of being lifted over the shoulders 65 so that the back may be uncovered as shown 70 in Fig. IV, while all the other parts of the body remain concealed from view by the frontal and skirt portions of the garment.

My improved garment may be used alone 75 as a sole body covering in the manner explained, as a lounging robe, and as a bathing or beach robe, as well as in other capacities which may suggest themselves to the wearer. From the foregoing it is clearly evident that the garment is inexpensive to make, 80 easily and quickly put on and taken off, held in place on the person without the aid of buttons or other fastening devices likely to result in injury or discomfiture, and moreover does not in any way hamper or restrict 85 free movement of the limbs.

Having thus described my invention, I claim:

1. A slip-on garment consisting of a substantially oblong piece of material having lateral incisions defining an upper body covering and a skirt section adapted to be wrapped about the lower part of the wearer's body, said upper body covering having an 90 opening adapted for passage of the head therethrough and including a cape portion 95 capable, when the garment is worn, of being lifted over the shoulders to expose the back 100 of the wearer.

2. A slip-on garment consisting of a substantially oblong piece of material having laterally aligned incisions in the longer sides thereof to define an upper cape portion and a lower skirt section connected by a narrower waist portion, said upper section being provided with a centrally disposed head opening and defining a cape portion capable, when the garment is worn, of being lifted over the shoulders to expose the back of the wearer, and the skirt section being adapted to be wrapped about the lower part of the wearer's body to effectively conceal the same whether the back is exposed or not.
3. A slip-on garment consisting of a substantially oblong piece of fabric having a centrally located opening, adapted for passage of the head therethrough and disposed nearer a shorter edge thereof, and aligned lateral incisions in the longer sides intermediate the head opening and the other short side to set apart an upper body covering including a cape portion serving, when the garment is worn, to drape the back of the wearer and capable when lifted over the shoulders of exposing the wearer's back, and a skirt portion adapted to be wrapped about the lower part of the wearer's body and secured at the waist to effectively conceal those portions of the wearer below the waist line whether the back is exposed or not.

In testimony whereof, I have hereunto signed my name at Erie, Pa., this 14th day of May, 1929.

CELINA C. CAMERON.

35. 40

45

50

55

60

65